UNITED STATES PATENT OFFICE.

ERNEST T. BECK, OF MERIDEN, CONNECTICUT, ASSIGNOR TO INTERNATIONAL SILVER CO., OF MERIDEN, CONNECTICUT, A CORPORATION OF NEW JERSEY.

DESIGN FOR A FLOWER HOLDER.

Application filed May 29, 1925. Serial No. 13,596. Term of patent 14 years.

To all whom it may concern:

Be it known that I, ERNEST T. BECK, a citizen of Germany, residing at Meriden, in the county of New Haven and State of Connecticut, have invented a new, original, and ornamental Design for a Flower Holder, of which the following is a specification, reference being had to the accompanying drawing, forming part thereof.

Fig. 1 is a plan view of a portion of the design, it being understood that the remaining portion left blank within the circle is a repetition of the part shown.

I claim:

The ornamental design for a flower holder as shown.

ERNEST T. BECK.
